[57] CLAIM

The ornamental design for a chair, as shown and described.

DESCRIPTION

FIG. 1 is a perspective view of a chair showing my new design;

FIG. 2 is a front elevational view thereof;

FIG. 3 is a right side elevational view thereof;

FIG. 4 is a rear elevational view thereof;

FIG. 5 is a top plan view thereof; and,

FIG. 6 is a perspective view of an alternative embodiment of my new design in which there is a cutout at the base of the back of the chair and the back of the chair has a shaped top.

FIG. 1

FIG. 2

FIG. 3

FIG. 4

FIG. 5

FIG. 6
